DESIGN FOR A CIGARETTE CASE OR SIMILAR ARTICLE

Thomas F. Cannon, Kew Gardens, N. Y.

Application December 23, 1941, Serial No. 104,807

Term of patent 3½ years

To all whom it may concern:

Be it known that I, Thomas F. Cannon, a citizen of the United States of America, residing in Kew Gardens, county of Queens, and State of New York, have invented a new, original, and ornamental Design for a Cigarette Case or Similar Article, of which the following is a specification, reference being had to the accompanying drawing, forming part thereof, wherein,

Figure 1 is a front elevational view of a cigarette case or similar article showing my new design.

Figure 2 is a side elevational view thereof, and

Figure 3 is a front edge elevational view of the article.

The rear surface of the cigarette case is ornamented substantially the same as the front, and the rear edge surface substantially the same as the front edge, except for the omission of the lip portion and the inclusion of the hinge as shown in Figs. 1 and 2.

I claim:

The ornamental design for a cigarette case or similar article, substantially as shown and described,

THOMAS F. CANNON.
